[57] CLAIM

The ornamental design for a combination seat and cover for hunters, as shown and described.

DESCRIPTION

FIG. 1 is a rear perspective view of a combination seat and cover for hunters being worn as a backpack showing my new design;

FIG. 2 is a perspective view of my combination seat and cover for hunters shown in use;

FIG. 3 is a top end view of my combination seat and cover for hunters in an inverted orientation;

FIG. 4 is a bottom end elevational view thereof;

FIG. 5 is a side elevational view thereof;

FIG. 6 is a side elevational view of the side opposite to that shown in FIG. 5;

FIG. 7 is a top view thereof; and,

FIG. 8 is a bottom view thereof.

The broken line disclosure of FIGS. 1 and 2 is for illustrative purposes only, and forms no part of the claimed design.
